UNITED STATES PATENT OFFICE.

WILLIAM C. BAXTER, OF BEVERLY, MASSACHUSETTS, ASSIGNOR TO UNITED SHOE MACHINERY COMPANY, OF PATERSON, NEW JERSEY, A CORPORATION OF NEW JERSEY.

POWER-TRANSMISSION DEVICE.

1,187,415.

Specification of Letters Patent. Patented June 13, 1916.

Application filed July 8, 1915. Serial No. 38,685.

To all whom it may concern:

Be it known that I, WILLIAM C. BAXTER, a citizen of the United States, residing at Beverly, in the county of Essex and State of Massachusetts, have invented certain Improvements in Power-Transmission Devices, of which the following description, in connection with the accompanying drawings, is a specification, like reference characters on 10 the drawings indicating like parts in the several figures.

This invention relates to power transmission devices and particularly to mechanism in which movements in the same direction 15 are imparted intermittently to a driven member from an operating device which moves alternately in opposite directions.

An object of the invention is to provide 20 an improved device of this class which shall be positive and uniform as well as substantially noiseless in its action and shall operate with but little wear in the connection between the driving and the driven members.

To this end an important feature of the 25 invention consists in a novel construction and arrangement of mechanism including positive means for effecting alternately engagement and disengagement between the driven member and the operating device to cause said device to be retracted in its idle movement while out of engagement with the driven member. The construction selected 30 for purposes of illustration comprises pawl and ratchet mechanism including means for moving the pawl positively into and out of engagement with the ratchet member. This construction avoids the wear upon the pawl and the ratchet teeth which would be caused 35 by engagement of the pawl with the teeth during the retracting movement of the pawl, as well as the noise which would be incident to such movement of the pawl over the teeth. The pawl, moreover, is so arranged relatively to the operating means and the ratchet 40 member that the tendency of the operating means is to maintain the pawl in effective engagement with the ratchet member during the forward movement and this tendency is increased by resistance to the movement of 45 said member, and this arrangement constitutes a further important feature of the invention.

The above and other features of the in-

vention, including certain details of construction and combinations of parts, will now be described with reference to the accompanying drawings and pointed out in the claims.

The invention is herein shown as embodied in mechanism particularly constructed and arranged for driving the stock feeding rolls of a heel lift cutting machine such as forms the subject matter of my co-pending application Serial No. 13,673, filed 60 March 11, 1915. It will be understood, however, that the invention is not restricted in its application to machines of this type nor in its broader aspects to the illustrated constructional details.

In the drawings:—Figure 1 is a fragmentary view of a portion of a cutting machine such as that shown in the above mentioned application, including mechanism in which the present invention is embodied; Fig. 2 is 75 a view in elevation and partly in section of a portion of the mechanism shown in Fig. 1, and Fig. 3 shows in elevation and partly in section a portion of the mechanism as viewed from the left with reference to Fig. 2. 80

A portion of the machine frame is seen at 2, and mounted on the frame is a bracket 4 which has supporting means for a pair of intermeshing pinions 6 and 8 from which movement is imparted to the feed rolls of 85 the machine through connections not shown herein but illustrated in the co-pending application above mentioned. The pinion 6 is driven from the pinion 8 and the latter pinion is driven by a gear wheel 10 mounted 90 loosely upon a shaft 12 which is supported by the bracket 4. The gear 10 is driven by pawl and ratchet mechanism which includes a ratchet wheel 14 mounted loosely upon a hub 16 formed on said gear. The gear 95 wheel and the ratchet wheel are provided in their adjacent faces with recesses in which are positioned balls 18, these balls operating normally to lock the wheels together so that movement is imparted to the gear wheel 100 from the ratchet wheel. The gear wheel 10 is arranged to move also lengthwise upon the shaft 12 against the tension of a spring 20 to permit the balls 18 to move out of locking relation to the ratchet wheel 14 when 105 the operation of the feed rolls is for any reason prevented, the ratchet wheel being restricted from similar movement in the oppo-

site direction by engagement with the side of the bracket 4.

The device for driving the ratchet wheel 14 comprises a pawl carrier 22 mounted to oscillate upon the shaft 12, and pivoted to this carrier by means of a stud shaft 24 is a pawl which comprises an arm 26 and a member 28 formed, in the construction shown, with a plurality of teeth for engagement with the teeth of the ratchet wheel, this member being mounted upon a stud 30 secured to the arm 26 and having a pin 32 to position it in fixed relation to the arm. The pawl is thus permitted to rock or swing 15 relatively to the carrier 22 about the axis 24 into and out of engagement with the teeth of the wheel 14. The pawl and its carrier are operated to impart movement to the ratchet wheel through connections including a link or pitman 34 pivoted on the stud 30 and driven by suitable means not herein shown in detail.

The pawl carrier 22, upon the opposite side of the shaft 12 from its connection with the pawl, is provided with a socket 36 in which is mounted a plunger 38 in position to bear frictionally upon the side of the bracket 4. The plunger is maintained in engagement with the bracket by means of a spring 40 the tension of which may be adjusted by means of a screw 42.

By reference to Fig. 3 it will be seen that movement of the pawl about the axis 24 in the direction to cause it to disengage the teeth of the wheel 14 is limited by engagement of a projection 44 on the arm 26 with a shoulder 46 on the carrier 22, while its movement in the opposite direction about the axis 24 is limited by its engagement with the wheel. By reason of this arrangement, and the friction of the plunger 38 upon the bracket 4 which tends to retard the movement of the carrier 22, the effect of reciprocation of the pitman 34 is first to rock the pawl about its axis 24 to cause it to engage or to disengage the wheel and then to move the pawl and the carrier together about the axis of the wheel. The pawl is thus disengaged from the teeth of the ratchet wheel before the pawl and the carrier are retracted on their idle stroke, so that during such retracting movement the pawl is maintained out of engagement with the wheel, with a consequent absence of noise and friction. Upon the forward stroke the pawl is first rocked positively into engagement with the wheel and is then moved together with the carrier to operate the wheel. It will be seen, moreover, that by reason of the arrangement of the axis 24 of the pawl relatively to the wheel 14 and the pitman 34, the pitman not only imparts to the pawl its forward or operative movement but tends to maintain the pawl in engagement with the wheel during such

movement, and that this tendency is increased in proportion to increase in resistance to movement of the wheel. Engagement of the pawl with the teeth of the wheel without slipping is thus effectively 70 insured.

It should be understood that in the use of the terms "pawl" and "ratchet member" or "ratchet wheel" in the claims it is not applicant's intention, except as required by the 75 context, to limit the claims to devices having details of construction such as shown, but to comprehend a broad range of equivalent constructions adapted to perform the required functions.

Having described the invention, what I claim as new and desire to secure by Letters Patent of the United States is:—

1. A device of the class described comprising, in combination, a ratchet member, 85 a pawl carrier and a pawl thereon for imparting movement to said member, said pawl being arranged for limited movement relatively to the carrier to engage or disengage the ratchet member, and means for imparting movement to said carrier through connection with the pawl, said means being arranged to move the pawl into or out of engagement with the ratchet member prior to movement of the carrier.

2. A device of the class described comprising, in combination, a ratchet member, a pawl carrier and a pawl thereon for imparting movement to said member, said pawl being arranged for limited movement relatively to the carrier to engage or disengage the ratchet member, operating means for the pawl carrier connected to the pawl to cause it to move the pawl relatively to the carrier into or out of engagement with the ratchet member prior to movement of the carrier, and means for retarding movement of the carrier to insure said limited movement of the pawl.

3. A device of the class described comprising, in combination, a ratchet member, a pawl carrier and a pawl thereon for imparting movement to said member, said pawl being pivoted on the carrier for rocking movement into or out of engagement with the ratchet member, and means for imparting movement to said carrier through connection with the pawl, said means being arranged to rock the pawl to cause it to engage or disengage the ratchet member prior to movement of the carrier.

4. A device of the class described comprising, in combination, a ratchet wheel, an oscillatory pawl carrier, a pawl mounted on said carrier for limited movement relatively to the carrier into or out of engagement with the ratchet wheel, and means for oscillating the carrier through connection with the pawl, said means being arranged to move the pawl into and out of engagement with

the ratchet wheel prior to the respective movements of the carrier in opposite directions.

5. A device of the class described comprising, in combination, a ratchet wheel, an oscillatory pawl carrier, a pawl pivoted on said carrier for limited rocking movement relatively to the carrier into or out of engagement with the ratchet wheel, means for oscillating the carrier, said means being connected to the pawl to impart said rocking movement to the pawl, and means for retarding the movement of the carrier to insure movement of the pawl relatively to the carrier prior to movement of the carrier.

6. A device of the class described comprising, in combination, a ratchet wheel, an oscillatory pawl carrier, a pawl pivoted on said carrier for rocking movement into or out of engagement with the ratchet wheel, operating means for rocking the pawl in both directions, said means being movable to effect a forward movement of the ratchet wheel after the pawl has engaged the wheel, means for limiting the disengaging movement of the pawl relatively to the carrier to cause the carrier to be retracted upon a movement of said operating means in the reverse direction, and means for retarding the movement of the carrier to insure the rocking movement of the pawl prior to movement of the carrier.

7. A device of the class described comprising, in combination, a supporting bracket, a ratchet wheel on said bracket, a pawl carrier mounted to oscillate about the axis of said wheel, a pawl pivoted on said carrier for limited rocking movement into or out of engagement with the ratchet wheel, operating means for rocking the pawl, said means being movable to oscillate

said carrier through connection with the pawl, and means for generating friction between said bracket and carrier to insure movement of the pawl relatively to the carrier prior to movement of the carrier.

8. A device of the class described comprising, in combination, a ratchet member, a pawl carrier and a pawl thereon for imparting movement to said member, said pawl being arranged for limited movement relatively to the carrier to engage or disengage the ratchet member, and means operative through connection with the pawl for moving the pawl and the carrier to operate the ratchet member, the pawl being so arranged relatively to said operating means and the ratchet member that the operating means in its forward movement has a tendency to maintain the pawl in effective engagement with the ratchet member increasing in proportion to increase in resistance to the movement of said member.

9. A device of the class described comprising, in combination, a ratchet wheel, a pawl carrier mounted to oscillate about the axis of said wheel, a pawl pivoted on the carrier for movement into or out of engagement with the ratchet wheel, and means operative through connection with the pawl for moving the pawl and the carrier to operate the ratchet wheel, the axis of the pawl being so located relatively to said operating means and the ratchet wheel that the operating means in its forward movement has a tendency to maintain the teeth of the ratchet wheel and the pawl in mesh increasing in proportion to increase in resistance to the movement of said wheel.

In testimony whereof I have signed my name to this specification.

WILLIAM C. BAXTER.
